UNITED STATES PATENT OFFICE.

EDWARD C. NORTH AND WILLIAM L. KNAPP, OF PALMYRA, AND CHRISTOPHER H. BIERBAUM, OF BUFFALO, NEW YORK.

DUMPING WAGON OR CAR.

No. 875,727.

Specification of Letters Patent.

Patented Jan. 7, 1908.

Application filed April 6, 1907. Serial No. 366,664.

To all whom it may concern:

Be it known that we, EDWARD C. NORTH and WILLIAM L. KNAPP, citizens of the United States, and residents of Palmyra, in the county of Wayne and State of New York, and CHRISTOPHER H. BIERBAUM, a citizen of the United States, and resident of Buffalo, in the county of Erie and State of New York, have invented a certain new and useful Improvement in Dumping Wagons or Cars, of which the following is a specification.

This invention relates to a dumping wagon or car of that type in which the load is carried by rotatable receptacles or trays.

15 The object of this invention is to produce a dumping wagon or car of this character which has a larger capacity and can be arranged lower than those heretofore in use and which is so constructed that the load 20 may be readily dumped at either side or at the middle of the road over which the wagon or car is drawn.

In the accompanying drawings consisting of 2 sheets: Figure 1 is a vertical longitudinal section taken in line 1—1, Fig. 2, and showing 25 our invention applied to an ordinary wagon. Fig. 2 is a fragmentary top plan view of the same. Fig. 3 is a fragmentary vertical section, on an enlarged scale, taken in line 3—3, Fig. 2. 30 Fig. 4 is a sectional view, on an enlarged scale, taken in line 4—4, Fig. 6. Fig. 5 is a fragmentary horizontal section taken in line 5—5, Fig. 6. Fig. 6 is a fragmentary front elevation, on an enlarged scale and partly in section, of our improved dump wagon. Fig. 7 is a rear elevation thereof. Fig. 8 is a cross section, on an enlarged scale, in line 8—8, Fig. 1. Fig. 9 is a top plan view showing the manner in which the trays may be arranged 40 when the invention is applied to a railway car.

Similar letters of reference indicate corresponding parts throughout the several views.

45 Our improvement may be organized so as to be applicable to wagons and cars in common use or the same may be embodied in wagons or cars which are specially constructed for this purpose.

50 In Figs. 1 to 8 of the drawings, our improvement is adapted to fit an ordinary wagon the running gear of which consists essentially of front and rear axles A, A¹ having wheels a, a¹, a front bolster B arranged above the

front axle and provided at opposite ends 55 with upright stakes b, a rear bolster C arranged above the rear axle and provided at opposite ends with upright stakes c, a longitudinal reach D connecting the front bolster with the rear bolster and axle and a king pin 60 d pivotally connecting the front bolster and reach with the front axle. Our improvement applied to this form of wagon is constructed as follows:

E, E represent a pair of standards mounted on the front bolster and F, F a pair of standards mounted on the rear bolster. The standards of each pair are arranged on opposite sides of the longitudinal center of the wagon and are connected by a transverse 70 bar g, thereby forming frames for supporting the movable parts of the dumping apparatus. For the purpose of holding each pair of standards against movement on their bolster in a direction lengthwise of the wagon each of the 75 standards is provided at its lower end with a pair of depending cheeks or flanges h which straddle or engage with opposite sides of the bolster.

Between each standard and the adjacent 80 stake is arranged a horizontal brace or holder which preferably consists of inner and outer sections I, I¹. The opposing ends of these brace sections overlap each other and are adjustably connected with each other by a bolt 85 i passing through slots i¹ in the overlapping parts thereof while their opposite outer and inner ends are constructed in the form of jaws j, j¹ which embrace the adjacent stake and standard, respectively. The jaw of the 90 inner section is preferably connected with the adjacent standard by a bolt j² but the jaw of the outer section merely engages frictionally with the stake. By means of these adjustable braces the frames may be applied 95 to and securely held in place on the bolsters of wagons in which the distance between the stakes varies.

K, K¹ represent a pair of trays or receptacles which are arranged transversely side 100 by side between the front and rear bolsters and which are adapted to receive the load which is to be transported. Each of these trays is constructed in the form of a segment of a cylinder and consists of a transversely 105 curved body l forming the side walls and bottom of the tray and vertical walls l¹, l² arranged at opposite ends of the body. These

trays are rotatable about horizontal parallel axes so that the opening of the same may be turned upwardly for receiving the load or turned downwardly for discharging the load.

5 For this purpose the front and rear end walls of each tray are provided on their outer sides with trunnions m , m^1 which are arranged axially in line and which are journaled respectively in bearings M formed at the upper 10 ends of the corresponding front and rear standards on the same longitudinal side of the wagon. These bearings are preferably open on their upper sides and the trunnions are confined in the same by means of cotter 15 pins n passing through the standards above the bearings.

The axis of each tray is below the center from which the curved body is described. The bodies of the trays are so constructed 20 that when they are in their closed or load receiving position the inner edges of both bodies engage each other at a point horizontally in line with the axes of both trays while their outer edges extend above said axes. 25 When both trays are filled the heap of material extends over the inner edges of the same and as the heap of material is usually higher at the middle than at the sides a greater amount of the same is contained 30 within the inner portions of the trays than in the outer portions thereof. In order to compensate for this difference the trunnions of each tray are placed a sufficient distance inwardly relatively to the point or 35 center k from which the body of the tray is described to balance the weight of the material within the tray on opposite sides of the center about which it rotates, as most clearly shown in Figs. 7 and 8. By this means the 40 devices which hold the trays in place are relieved from undue strain and it also enables the attendant to easily dump the load and reliably control the same.

When it is desired to dump the load in the 45 trays along the middle of the road over which the wagon is moving the same are turned so that the inner longitudinal sides or edges thereof are depressed. And if it is desired to dump the trays along the side of the 50 road over which the wagon is traveling the same are turned so that the outer longitudinal sides of the same are depressed.

In order to permit of carrying the end walls upwardly a sufficient distance to confine the load against spilling from the trays at the front and rear ends thereof and still permit the trays to turn freely downwardly on their inner sides relatively to each other the inner portions o of the edges of these end 60 walls diverge upwardly from the meeting line at the inner longitudinal sides of the bodies. The edges o are preferably curved concentrically with the axes of the trays, as shown best in Fig. 8, and the spaces between 65 these curved edges of each pair of companion

end walls is closed by an upright shutter or bridge plate P .

When dumping the trays inwardly the material is prevented from lodging on the reach of the wagon by means of a deflector 70 which preferably consists of two inclined or curved plates q , q arranged lengthwise above the reach and between the trays and diverging from their upper connected ends downwardly beyond the opposite sides of the 75 reach. These deflecting plates are preferably secured at opposite ends to the front and rear cross bars of the standards so that they are immovable and the lower ends of the shutter plates P , are secured to opposite 80 ends of the deflector, as shown in the drawings.

Various means may be provided for permitting the trays to be simultaneously dumped either inwardly or outwardly or to permit 85 each tray to be dumped inwardly or outwardly independently of the other tray. The means for this purpose shown in the drawings, as an example, are constructed as follows: R represents a horizontal operating 90 shaft arranged transversely above the front trunnions of both trays and provided near opposite ends with two worms r which mesh with worm-wheels s on said front trunnions. These worms and their co-operating worm 95 wheels have their threads and teeth trending in opposite directions so that when the shaft R is turned in one direction both trays will be depressed on their inner sides for discharging the load along the middle of the road 100 while upon turning the shaft in the other direction the trays will be depressed at their outer sides for discharging the load along the side of the road. Any suitable means may be employed for operating this shaft, that 105 shown in the drawings being suitable for this purpose and consisting of a ratchet wheel T secured to the central portion of the shaft, a rocking hand lever t mounted loosely on the shaft adjacent to the ratchet wheel, a pawl 110 pivoted on the hand lever and having front and rear dogs or teeth u , u^1 projecting from opposite sides of its pivot and an upwardly projecting lug u^2 arranged centrally between 115 its teeth, and a spring v arranged between said lug and an abutment v^1 on the hand lever and operating to hold either of said dogs or teeth yieldingly in engagement with the teeth of the ratchet wheel. As shown in Fig. 4, the front tooth of the pawl is in engagement with the ratchet wheel and upon reciprocating the hand lever while the pawl is in this position the shaft will be turned in the direction of the arrow Fig. 4. The pawl is thus held with its front tooth in engagement with the teeth of the ratchet wheel by reason of the connection between the lug u^2 and spring v being in front of the dead center 120 between the pivot of the pawl and the abutment v^1 . Upon shifting the pawl by hand 125

so that the point of connection between the lug u^2 and the spring v is in rear of the dead center, the rear tooth of the pawl will engage the ratchet wheel and cause the shaft to be turned intermittently in the opposite direction upon rocking the hand lever.

It is sometimes desirable to dump the contents of only one of the trays either at the middle or at the side of the roadway while the contents of the other tray are not disturbed, this being the case where uniform distribution or grading of the material is required. To permit of this, means are provided for disconnecting either of the trays from the turning device. The preferred means for this purpose which are best shown in Figs. 1, 2, 3 and 6, consist of two rotating cams or eccentrics W journaled loosely at opposite ends of the operating shaft and each engaging on its upper and lower sides with laterally projecting abutments or lugs w, w' formed on a bracket X on the outer side of the adjacent standard. Upon turning one of these eccentrics in one direction, the respective end of the shaft carried thereby is raised and the corresponding worm is disengaged from the companion worm-wheel while upon turning the eccentric in the opposite direction said end of the shaft will be lowered and the corresponding worm will be engaged with its worm-wheel. When one of the worms is thus lifted out of engagement from its worm-wheel the corresponding tray will be unaffected by the rotation of the shaft while dumping the other tray. It will be observed that by this means the contents of either tray can be discharged at will, thus permitting of greater uniformity in the distribution of the material. Upon raising and lowering the ends of the shaft the same are guided in vertical slots x^1 in the brackets which receive those portions of the shaft between the worms and the eccentrics.

While either one of the trays is uncoupled from the turning mechanism the same is held in place by means of a locking device which is preferably so constructed that the locking of the tray is effected automatically and simultaneously upon disengaging the same from the turning mechanism. As shown in Figs. 2, 3, and 6, the turning of each eccentric is effected by means of a handle or rock arm y arranged on the outer side of the same. This handle projects upwardly when the corresponding worm is in its operative position and downwardly when said worm is in its inoperative position. On its front side each eccentric arm is provided with a tooth y^1 and each tray is provided on the outer side of its front wall with a segmental row of teeth y^2 forming a toothed rack which is arranged concentrically with the axis of rotation of the respective tray. When the worm and worm-wheel of one tray are in mesh and the corresponding eccentric arm projects upwardly

the tooth on the latter is disengaged from the teeth on the adjacent tray permitting this tray to be turned. But when the eccentric arm is moved downwardly and disengages the respective worm-wheel and worm, the tooth of said arm engages between two teeth of the rack and holds the respective tray against turning. By providing a segmental row of these teeth for each tray it is possible to uncouple the same from the turning mechanism and hold the tray against accidental displacement either in its normal filled position or in its abnormal or partly dumped position.

By employing two trays side by side for supporting the load a greater amount of material can be carried in a wagon of given dimensions, a much stronger structure is produced owing to the division of the load between the two trays, the wear upon the parts is reduced and the weight of the load is better distributed.

Furthermore this construction of dumping wagon permits of carrying the load nearer the ground which reduces the danger of tipping and also permits of dumping the load either at the middle or at the side of the road, thereby reducing the amount of labor for subsequently grading or evening up the material after it is dumped.

It will be observed that all of the devices whereby the trays are manipulated are arranged within convenient reach of the driver's seat z which is mounted on the front of the wagon enabling him to maintain control of the horses and attend to the dumping mechanism without leaving the seat.

When our improved dumping device is used on railway cars two or more pairs of such rotary trays may be mounted on the same car and operated by mechanism constructed substantially like that shown in Figs. 1, 2, 3, 4 and 6. As shown in Fig. 9, two pairs of such trays K^1, K^3 are represented as mounted end to end on a car platform K^4 .

It is obvious that our improved dumping mechanism is applicable to wagons as ordinarily constructed as well as to wagons which may be especially constructed to receive our improvements.

We claim as our invention:

1. A dumping wagon or car having two vertically turning trays arranged side by side and adapted to meet normally at their inner edges, the axes of said trays being arranged inwardly from the longitudinal center of the trays, substantially as set forth.

2. A dumping wagon or car having two trays pivoted parallel to each other and each having a curved body and end walls, the inner edges of said bodies meeting each other and being in line with the axes of the trays in the normal position thereof, substantially as set forth.

3. A dumping wagon or car having two trays pivoted parallel to each other and each having a curved body and end walls, the inner edges of said bodies meeting each other and being in line with the axes of the trays in the normal position thereof and the opposing inner edges of each pair of corresponding end walls diverging upwardly, substantially as set forth.
4. A dumping wagon or car having two trays pivoted parallel to each other and each having a curved body and upright end walls, the inner edges of said bodies meeting each other and being in line with the axes of the trays in the normal position thereof and the opposing inner edges of each pair of corresponding end walls diverging upwardly, substantially as set forth.
5. A dumping wagon or car having two trays pivoted parallel to each other and each having a curved body and upright end walls, the inner edges of said bodies meeting each other and being in line with the axes of the trays in the normal position thereof and the opposing inner edges of each pair of corresponding end walls diverging upwardly and shutter or bridge plates arranged to close the spaces between the inner portions of said end walls, substantially as set forth.
6. A dumping wagon or car having two trays pivoted parallel to each other and each having a curved body and upright end walls, the inner edges of said bodies meeting each other and being in line with the axes of the trays in the normal position thereof and the inner portion of the edge of each end wall being curved upwardly from the meeting point of the inner edges of the bodies concentrically with the axis of the respective body, substantially as set forth.
7. A dumping wagon or car having two trays pivoted parallel to each other and each having a curved body and upright end walls, the inner edges of said bodies meeting each other and being in line with the axes of the trays in the normal position thereof and the inner portion of the edge of each end wall being curved upwardly from the meeting point of the inner edges of the bodies concentrically with the axis of the respective body, and shutter or bridge plates secured at their lower ends to a stationary part while their upper ends extend across the spaces between the inner edges of the end walls, substantially as set forth.
8. A dumping wagon or car comprising a running gear having a reach, a pair of trays arranged lengthwise side by side and pivoted parallel, and a deflector arranged between said trays and above said reach, substantially as set forth.
9. A dumping wagon or car comprising a running gear having a reach, a pair of trays arranged lengthwise side by side and pivoted parallel, and a deflector arranged between said trays and above said reach and consist-
- ing of two plates which are connected at their upper edges and diverge downwardly beyond the sides of the reach, substantially as set forth.
10. A dumping wagon or car comprising a running gear, pairs of bearings arranged on the front and rear parts of said running gear, two trays arranged side by side and having trunnions journaled in said bearings, an operating shaft, and worms arranged on said shaft and meshing with worm wheels on corresponding trunnions of the trays, substantially as set forth.
11. A dumping wagon or car comprising a running gear, pairs of bearings arranged on the front and rear parts of said running gear, two trays arranged side by side and having trunnions journaled in said bearings, an operating shaft having worms meshing with worm wheels on corresponding trunnions of said trays, a ratchet wheel arranged on the operating shaft, and a hand lever having a pawl engaging with said ratchet wheel, substantially as set forth.
12. A dumping wagon or car comprising a running gear, pairs of bearings arranged on the front and rear parts of said running gear, two trays arranged side by side and having trunnions journaled in said bearings, an operating shaft having worms meshing with worm wheels on corresponding trunnions of said trays, a ratchet wheel arranged on the operating shaft, a hand lever pivoted on the shaft, a pawl pivoted on said lever and having teeth on opposite sides of its pivot and a central lug, and a spring interposed between said lug and an abutment on said lever and operating to yieldingly hold either tooth of said pawl in engagement with said ratchet wheel, substantially as set forth.
13. A dumping wagon or car comprising a running gear, pairs of bearings arranged on the front and rear parts of said running gear, two trays arranged side by side and having trunnions journaled in said bearings and means for moving either of said worms into and out of engagement from its companion worm wheel, substantially as set forth.
14. A dumping wagon or car comprising a running gear, pairs of bearings arranged on the front and rear parts of said running gear, two trays arranged side by side and having trunnions journaled in said bearings and means for moving either of said worms into and out of engagement from its companion worm wheel comprising an eccentric pivoted on the shaft, and a stationary support on which said eccentric turns, substantially as set forth.
15. A dumping wagon or car comprising a running gear, pairs of bearings arranged on the front and rear parts of said running gear, two trays arranged side by side and having trunnions journaled in said bearings and means for moving either of said worms into

and out of engagement from its companion worm wheel comprising an eccentric pivoted on the shaft, a bracket having a slot which receives said shaft, and abutments arranged 5 on said bracket and engaging with the upper and lower sides of the eccentric, substantially as set forth.

16. A dumping wagon or car comprising a running gear, pairs of bearings arranged on 10 the front and rear parts of said running gear, two trays arranged side by side and having trunnions journaled in said bearings and means for holding said trays against turning consisting of a rotary arm pivoted on a stationary support and adapted to engage with 15 teeth on the tray, substantially as set forth.

17. A dumping wagon or car comprising a running gear, pairs of bearings arranged on the front and rear parts of said running gear, 20 two trays arranged side by side and having trunnions journaled in said bearings and means for holding said trays against turning consisting of a rotary arm pivoted on a stationary support and adapted to engage with 25 a segment toothed rack on the tray, substantially as set forth.

18. A dumping wagon or car comprising a running gear, pairs of bearings arranged on the front and rear parts of said running gear, 30 two trays arranged side by side and having trunnions journaled in said bearings, means for turning said trays, means for uncoupling either of said trays from the turning mechanism and a holding device for each of said trays 35 which simultaneously operates to hold the tray when the latter is uncoupled from the turning mechanism, substantially as set forth.

19. A dumping wagon or car comprising a 40 running gear, pairs of bearings arranged on the front and rear parts of said running gear, two trays arranged side by side and having trunnions journaled in said bearings, a transverse shaft provided with worms meshing 45 with worm wheels on corresponding trunnions of the trays, eccentrics turning on the ends of said shaft and engaging with stationary supports, segment toothed racks arranged on the trays, and rock arms arranged 50 on the eccentrics and each having a tooth

which is adapted to engage with one of said racks, substantially as set forth.

20. A dumping wagon comprising a running gear having front and rear bolsters, standards arranged on said bolsters and having lugs engaging opposite sides of the same 55 and trays pivoted on said standards, substantially as set forth.

21. A dumping wagon comprising a running gear having front and rear bolsters, 60 pairs of standards arranged on the front and rear bolsters, a transverse bar connecting each pair of standards, and trays pivoted on said standards, substantially as set forth.

22. A dumping wagon comprising a running gear having front and rear bolsters and stakes rising from opposite ends of each 65 bolster, pairs of standards arranged on the front and rear bolster, trays pivoted on the standards, and braces interposed between 70 the standards and said stakes, substantially as set forth.

23. A dumping wagon comprising a running gear having front and rear bolsters and stakes rising from opposite ends of each 75 bolster, pairs of standards arranged on the front and rear bolster, trays pivoted on the standards and braces interposed between the standards and said stakes and each consisting of overlapping inner and outer sections having jaws which engage respectively with the corresponding standard and stake, a bolt connecting the inner jaw with the standard and a bolt and slot connection between the brace sections, substantially as 80 set forth.
